ELECTRIC DISCHARGE TUBE WITH INTERNAL CONDENSER CONSTRUCTION

Gerrit Hendrik Petrus Alma, Kornelis Swier Knol, Pieter Nicolaas Kuiper, Frits Prakke, Maximiliaan Julius Otto Strutt, and Aldert van der Ziel, Eindhoven, Netherlands, assignors to Hartford National Bank and Trust Company, Hartford, Conn., as trustee

Application July 20, 1946, Serial No. 685,185
In the Netherlands September 10, 1943

Section 1, Public Law 690, August 8, 1946
Patent expires September 10, 1963

3 Claims. (Cl. 250—27.5)

1

This invention relates to electric discharge tubes comprising built-in condensers.

It is generally known to house condensers and other elements pertaining to the circuit-arrangement, which are usually located outside the tube, within the latter, which is advantageous, more particularly with tubes for short and ultra short waves, since in this case the connections between electrodes and circuit elements are required to be short. However, built-in condensers involve complications in the construction of the interior of these tubes, whilst with the use for short and ultra short waves the actually short connections between electrodes and condensers frequently still have an excessively high self-induction.

The above-mentioned drawbacks may be obviated by using a discharge tube according to the present invention, which tube comprises one or more condensers housed in the interior, these condensers constituting at the same time constructional elements of the electrode system. By "constructional elements" are meant in this case bodies which are connected, either directly or indirectly, to the electrodes and which act in some way or other as supporting members, screening members and the like. Thus, for example, use may be made of plate-shaped condensers consisting of a plate made of insulating material, for example mica, and coated on both sides with a silver layer. Such a plate may be arranged at the top or at the bottom of the electrode system and may act at the same time as a screening member, as a condenser and as a supporting member.

Another possible form of construction of condensers built-in in a discharge tube according to the invention consists in that one or more supporting rods of the electrodes are built up from two or more than two coaxial conductors which are separated by insulating material. The conductive layers constitute in this case the various coatings of the condenser; these coatings are separated by insulating material which acts as the dielectric. The above-described rod-shaped condensers may be constructed, for example, as drawn condensers, two or more conductors being arranged around one another with the interposition of insulating material and being drawn out to a smaller diameter by swaging and drawing. Since the distance between these conductors may be very small, such a condenser may have a high capacity per unit of length, for example from 10 to 100 micromicrofarads per centimeter, according to the dielectric and the distance between the conductors. With these drawn condensers the

2

conductors may consist of copper, nickel or similar material and are separated by an intermediate layer of magnesia, titanium oxide or similar insulating material.

Thus, while the considerations of construction make it advantageous to utilize discharge tubes according to the present invention both for long- and short-wave purposes, the invention is of particular importance for tubes operating on short and ultra-short waves, since in these applications the advantage of the elimination of special connections between the condensers and the electrodes is of very great importance not only from the point of view of construction, but also from the electric viewpoint. Thus, for example, the invention may be advantageously applied to tubes for decimeter and centimeter waves in order to increase the mutual capacity of determined electrodes and to obtain in this way a reduction of the output damping. For what purpose a discharge tube according to the invention may be used, we always have here a construction wherein the electrodes and the circuit elements are connected to one another in the shortest possible manner, that is, in many cases directly, without separate wires.

In order that the invention may be clearly understood and readily carried into effect, it will now be explained more fully with reference to the accompanying drawing, wherein

Fig. 1 represents diagrammatically a circuit-arrangement of a tube according to the invention, and

Figs. 2 and 3 show different forms of construction of such a tube.

In the figures, 1 designates the cathode, 2 the input control electrode, 3 the anode, which generally consists in such tubes of two plates connected to one another by a strap, 4 designates a screen grid and 5 a suppressor grid. The screen grid 4 is capacitively coupled to the electrode 5. A tube 20 is shown enclosing these elements.

In order to obtain a symmetrical arrangement and to keep the input circuit and the output circuit separated from one another as completely as possible, the cathode 1 has two supply conductors, whilst the electrodes 4 and 5 are connected or coupled to the cathode on two sides. With decimeter- and centimeter waves this arrangement is very advantageous, since each supply wire acts as a self-inductance. With the arrangement according to Fig. 1 the input and the output of the tube are completely separated from one another. It is of very great importance that the condensers 6 should be connected directly

to the electrodes 4 and 5, with the use of connecting wires of the smallest possible length. In the form of construction according to Fig. 2 use is made of drawn condensers which act at the same time as supporting rods of the grid 5. The grid wires of this grid may be wound directly on the outer conductor 7 of the drawn condensers. The inner conductors 8 are connected to the screen grid 4 through the intermediary of very short straps 9. The grids 2 and 4 may be wound in the usual manner on supporting rods 14. In Fig. 2 the whole of the system is surrounded by a screening electrode 10 which is connected to the cathode and this screen is surrounded by an envelope 20.

In the form of construction according to Fig. 3 use is made of disc-shaped condensers. They consist of an insulating plate, for example of mica or ceramic material, to both sides of which is supplied by squirming a layer of silver. The electrodes 4 and 5 are fixed in the insulating plate by means of small flanged tubes. The silver layers are arranged in such a manner that the one plate makes contact with the flanged tubes of the grid 4 and leaves an open space around those of the grid 5, whereas the other silver layer is in contact with the flanged tubes of the grid 5, but is insulated from those of the grid 4. The flanged tubes may be provided with tags in order to ensure a better contact with the silver layer concerned.

In Fig. 3 the upper silver layer is in contact with the tags 13 of the electrode 4. In order to avoid excessive heating due to circulating currents during the degassing or during operation the silver layer may exhibit a gap 12. The silver layer which is in contact with the grid 5 acts at the same time as a screen. Such disc-shaped condensers are preferably arranged at two ends of the electrode system, where they replace the screens usually provided at these points. An envelope 20 is shown surrounding the electrode system.

The invention makes it possible to obtain the desired effect without the construction of the electrode system becoming appreciably complicated. It will be evident that the invention may also be applied when condensers are to be incor-

porated in tubes designed for other purposes, for example for the usual wave lengths. Furthermore, the two described forms of construction may be combined whilst, as the case may be, other forms of condensers may be possible.

5 What we claim is:

1. An electric discharge tube comprising an electrode system including a cathode, an anode, a plurality of grid elements having grid wires and interposed between said cathode and said anode, supporting rods adjacent the said grid elements, a supporting rod for one grid element consisting of an inner conductor, a cylindrical insulator encircling the said inner conductor and 10 a metallic cylinder encircling the cylindrical insulator constituting the supporting rod a cylindrical condenser, the said supporting rod engaging the said grid wires and supporting the said element at the encircling metallic cylinder thereof, and a short strap connecting the said inner conductor to an adjacent grid electrode.

15 2. An electric discharge tube as claimed in claim 1 in which a plurality of cylindrical condensers support a grid electrode, the grid electrode being connected to the outer metallic cylinders of the said condensers, and a plurality of short straps connecting the inner conductors of the said condensers to an adjacent grid electrode.

20 3. An electric discharge tube as claimed in claim 2, wherein the cylindrical condensers consist of drawn coaxial conductors, between which insulating material is provided.
